UNITED STATES PATENT OFFICE

2,610,029

DRILL FEED MECHANISM WITH RECIPROCATING NONROTATING FEED CYLINDER

Sterling C. Moon, Worthington, Ohio, assignor to
The Jeffrey Manufacturing Company, a corpora-
tion of Ohio

Application September 9, 1950, Serial No. 184,017

4 Claims. (Cl. 255—47)

1

This invention relates to a drill mechanism, and an object of the invention is to provide an improved device of this type in which there is a rotating auger tube which is fed in reverse directions by a hydraulic feed cylinder, jack or motor, the parts of which are essentially non-rotating.

Other objects of the invention will appear hereinafter, the novel features and combinations being set forth in the appended claims.

In the accompanying drawings:

Fig. 1 is a plan view showing a drilling machine incorporating the drill of my invention;

Fig. 2 is a side elevational view of the machine of Fig. 1;

Fig. 3 is a sectional view through the drilling mechanism; and

Fig. 4 is a sectional view taken on the line 4—4 of Fig. 3, looking in the direction of the arrows.

Referring first to Figs. 1 and 2 of the drawings, the drilling machine illustrated includes a main frame 10 supported upon front power driven traction wheels 11 and rear steerable wheels 12. Extending forwardly from the main frame 10 but rigidly attached thereto is a head 13. Pivotedly attached to the head 13 for swinging movement upon an upright axis is a yoke 14 which may be swung preferably through a full 180°, or 90° to each side of the longitudinal forward position, by means of reversible gearing including a reversible rotary hydraulic motor 15. The gearing may include the conventional worm and worm wheel.

An intermediate frame 16 extends forward from the yoke 14 and is pivotally attached thereto on a horizontal axis by pivot means 17. Swinging adjustment of the intermediate frame 16 about the horizontal axis of the pivot 17 is provided by a pair of hydraulic motors, cylinders or jacks 18, the rear ends of which are pivoted to the yoke 14, and the fronts of the piston rods of which are pivoted near the front and bottom of the intermediate frame 16.

Extending forward from the front of the intermediate frame 16 is a neck 19 which is rotatable about its longitudinal axis by appropriate drive gearing carried on the intermediate frame 16 and including a rotary hydraulic motor 20. At the outer end of the neck 19 there is a bracket 21 which is adjustable about an axis which is at right angles to the axis of the neck 19, this adjustment being effected by a drive mechanism, such as a worm and worm wheel drive, driven by a reversible rotary hydraulic motor 22.

Carried on top of the bracket 21 is a drill mechanism 23. By referring to Figs. 1 and 2 of the drawings it will be seen that the drill mechanism

23 and the boom upon which it is supported, which is formed principally by the yoke 14, intermediate frame 16 and neck 19, may be adjusted to a variety of positions including the positions in which said boom extends substantially at right angles on opposite sides of the longitudinal axis of the main frame 10. The drill 23 may also be raised and lowered and thus it may be positioned at any position over a wide face of a mine room.

Referring particularly to Figs. 3 and 4 of the drawings it will be seen that the drill mechanism 23 includes a two-piece housing comprising a rear cylinder member 24 to which a larger diameter forward cylinder member 25 is rigidly but removably attached by bolts or machine screws.

Mounted within the cylinder 25 on spaced forward and rearward bearings is a rotary drive cylinder 26 which at its left-hand end, as viewed in Fig. 3, is provided with an integral spur gear 27 which meshes with and is driven by a spur gear 28 carried on the rotor shaft of a reversible motor 29 which is preferably hydraulic, though it may be electric. The motor 29 is carried on a bracket 30 which is integral with the cylinder 25 and cooperates therewith to provide a housing for the gears 27 and 28.

At diametrically opposite sides the cylinder 26 is provided with a pair of removable longitudinally extending elongated keys 31 which extend through slots in said cylinder 26, as best illustrated in Fig. 4 of the drawings. The function of the keys 31 is to provide a driving connection between the driven cylinder 26 and a rotating auger tube 32 which is not only rotatable but is mounted for reciprocation within the housing 24.

That is, the rotating auger tube 32 extends through a central opening in a head 33 provided on the right-hand end of the housing tube 25. The front end of the auger tube 32 is provided with a head ring 33 rigidly attached to said tube 32, as by welding, to which head ring 33 a drill chuck or socket 34 is removably attached, said socket 34 being adapted to receive a drill bit in a conventional manner.

To provide for rectilinear longitudinal reciprocation of the auger tube 32 while it is driven as above described, the external surface thereof is provided with a pair of diametrically opposite longitudinal keyways 35 adapted to receive the elongated keys 31. To provide for the reciprocal motion of the rotary tube 32 and attached parts, including the chuck 34, I provide a double acting hydraulic cylinder type motor or jack including a cylinder 36, the left-hand end of which, as viewed in Fig. 3, is rigidly attached to a head 37.

of the housing cylinder 25 through the intermediary of a central axially projecting boss or projection 38 with which the cylinder 36 has a close contact.

A bore 39 extends through the head 37 and projection 38, providing a hydraulic passageway to the interior of the cylinder 36. Within the cylinder 36 there is a piston 40 of essentially standard construction, having reversely positioned leak-proof washers adjacent opposite ends thereof, to which a piston rod 41 is attached which extends through the cylinder 36. Rigidly attached to the right-hand end of the cylinder 36, as viewed in Fig. 3, is a head 42 which is provided with a stuffing box 43 which cooperates with the piston rod 41.

At its right-hand end the piston rod 41 is provided with a ball bearing 44, the inner race of which is clamped to the piston rod 41, the outer race of which is clamped to the head ring 133 and the base of the socket or drill chuck 34. This provides an important characteristic of my invention, in that it permits free rotation of the auger tube 32, its head ring 133 and the drill chuck 34 without requiring similar rotation of the piston rod 41 or the piston 40. It is particularly undesirable to rotate the piston 40 because this greatly shortens the life thereof.

It is obvious that if hydraulic fluid is delivered to the passageway 39 the piston 40, piston rod 41, rotary auger tube 32 and chuck 34 will be fed to the right or outwardly. During this feeding movement the interior surface of the rotating auger tube 32 is supported at the right-hand end by turning on the exterior of the head 42 which is preferably made of brass, bronze or the like. At its rear end the tube 32 is provided with a bearing guide ring 45 on its external surface which has sliding contact with the internal surface of the housing cylinder 24.

To provide for reverse or retracting movement of the drill chuck 34 and rotary tube 32 there is a pair of feed tubes 46 which extend from a fitting adjacent the rear end of the cylinder 24 between the cylinder 36 and the tube 32 and at their right-hand or forward ends communicate with a bore 47 formed in the head 42 and leading to the interior of the cylinder 36. Hydraulic fluid delivered to feed tubes 46 will tend to force the piston 40, piston rod 41, rotary auger tube 32 and chuck 34 rearwardly or to the left at a relatively high speed in view of the reduced effective cross-section of the cylinder 36 produced by the large diameter of the piston rod 41.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. A drill including a housing adapted to be held in fixed position during operation of the drill, an auger tube mounted for both rotation and rectilinear axial feeding motion in reverse directions relative to said housing and telescoping thereinto, a drill chuck attached to said auger tube, a feed cylinder rigidly attached to said housing and positioned inside it, said auger tube being mounted to reciprocate axially outside said feed cylinder and axially inside said housing, an operating piston reciprocable within said feed

cylinder, a piston rod attached to said piston adjacent one end of said piston rod, bearing means attaching the other end of said piston rod to said auger tube to impart rectilinear motion of said piston and piston rod to said auger tube while said auger tube is free to rotate relative to said piston and piston rod which are essentially non-rotary during operation of said drill, means for delivering fluid pressure to opposite ends of said piston to produce selective reverse rectilinear movement thereof, means for supporting and rotating said auger tube including a cylinder within said housing and surrounding said auger tube, bearing means supporting said cylinder within said housing for rotary motion, means slidably interconnecting said cylinder and auger tube whereby the latter is driven rotationally by the former, gear means on said cylinder, a motor carried by said housing, and a gear driven by said motor for driving said gear on said cylinder.

2. A drill including a housing adapted to be held in fixed position during operation of the drill, an auger tube mounted for both rotation and rectilinear axial feeding motion in reverse directions relative to said housing and telescoping thereinto, a drill chuck attached to said auger tube, a feed cylinder rigidly attached to said housing and positioned inside it, an operating piston reciprocable within said feed cylinder, a piston rod attached to said piston adjacent one end of said piston rod, bearing means attaching the other end of said piston rod to said auger tube to impart rectilinear motion of said piston and piston rod to said auger tube while said auger tube is free to rotate relative to said piston and piston rod which are essentially non-rotary during operation of said drill, means for delivering fluid pressure to opposite ends of said piston to produce selective reverse rectilinear movement thereof, means for supporting and rotating said auger tube including means forming a cylinder within said housing and surrounding said auger tube, bearing means supporting said cylinder forming means within said housing for rotary motion, means slidably interconnecting said cylinder forming means and said auger tube whereby the latter is driven rotationally by the former, and motor means for driving said cylinder forming means.

3. A drill including a housing adapted to be held in fixed position during operation of the drill, an auger tube mounted for both rotation and rectilinear axial feeding motion in reverse directions relative to said housing and telescoping thereinto, a drill chuck attached to said auger tube, a feed cylinder rigidly attached to said housing and positioned inside it, said auger tube being mounted to reciprocate radially outside said feed cylinder and radially inside said housing, an operating piston reciprocable within said feed cylinder, a piston rod attached to said piston adjacent one end of said piston rod, bearing means attaching the other end of said piston rod to said auger tube to impart rectilinear motion of said piston and piston rod to said auger tube while said auger tube is free to rotate relative to said piston and piston rod which are essentially non-rotary during operation of said drill, means for rotating said auger tube and drill chuck including means forming a cylinder within said housing and surrounding said auger tube, and means slidably interconnecting said cylinder forming means and auger tube whereby the latter is driven rotationally by the former.

4. A drill including a housing adapted to be

held in fixed position during operation of the drill, an auger tube mounted for both rotation and rectilinear axial feeding motion in reverse directions relative to said housing and telescoping therewith, a drill chuck attached to said auger tube, a feed cylinder rigidly attached to said housing and positioned inside it, an operating piston reciprocable within said feed cylinder, a piston rod attached to said piston adjacent one end of said piston rod, bearing means attaching the other end of said piston rod to said auger tube to impart rectilinear motion of said piston and piston rod to said auger tube while said auger tube is free to rotate relative to said piston and piston rod which are essentially non-rotary during operation of said drill, means for rotating said auger tube and drill chuck includ-

ing means forming a cylinder within said housing and surrounding said auger tube, and means slidably interconnecting said cylinder forming means and auger tube whereby the latter is driven rotationally by the former.
